UNITED STATES PATENT OFFICE.

EMIL L. KAMRATH, OF MILWAUKEE, WISCONSIN, ASSIGNOR, BY DIRECT AND MESNE ASSIGNMENTS, OF ONE-HALF TO HERMAN J. BAERWALD AND ONE-HALF TO CHARLES H. BAERWALD, BOTH OF MILWAUKEE, WISCONSIN.

FRICITION-GRIP HANGER.

Application filed March 23, 1923. Serial No. 627,062.

To all whom it may concern:

Be it known that I, EMIL L. KAMRATH, a citizen of the United States, and resident of Milwaukee, in the county of Milwaukee and State of Wisconsin, have invented certain new and useful Improvements in Friction-Grip Hangers; and I do hereby declare that the following is a full, clear, and exact description thereof.

10 The invention relates to improvements in hanging or supporting devices for articles, such as towels and the like, and is adapted particularly for ordinary household and office use.

15 It comprises a base and a U-shaped holder, the arms of the holder being divergent and each having a leg bent therefrom at substantially right angles and imbedded in the base. A ball is retained between the holder and the base and a hole is provided in the base between the upper ends of the arms of the holder.

20 The primary object of the invention is the provision of a U-shaped holder having divergent arms, whereby room is provided so that an article may readily be inserted between the base and the ball, the ball being movable upwardly into the space provided by the divergent arms. The divergent arms provide room also for the positioning of a screw in the hole in the base.

25 A further object of the invention is the provision of a hanger into which the insertion of an article to be held is facilitated especially by the shape of the base and the curvature of the holder at its lower end, immediately adjacent thereto. The holder is not directed at an angle with respect to the base, but is nearest to the base at a point 30 immediately above the lower end of the holder, so that room is provided for the convenient insertion of an article to be held.

35 A further object of the invention is the provision of a holder of especial simplicity, being of the shortest length possible for the performance of the function intended, and so shaped as to prevent accidental bending and release of the ball. From the U-shaped holder a pair of legs extend at right angles to the base and an arm is imbedded therein. The holder is not long and very considerable force must be exerted in order to deflect the wire.

With the above and other objects in view,

which will appear as the description proceeds, the invention resides in the novel construction, combination and arrangement of parts substantially as hereinafter described, and more particularly defined by the appended claim, it being understood that such changes in the precise embodiment of the herein disclosed invention may be made as come within the scope of the claim. 55

In the accompanying drawing is illustrated one complete example of the physical embodiment of the present invention constructed according to the best mode so far devised for the practical application of the principles thereof. 65

Figure 1 is a central sectional elevation 70 of the device taken on the line 1—1 of Figure 2.

Figure 2 is a front elevation thereof.

Figures 3 and 4 are sections on the lines 3—3 and 4—4, respectively, of Figure 1. 75

The base 10 is substantially rectangular, and the wire holder 11 is substantially U-shaped. Its arms 12—12' diverge slightly upwardly and at 13 the upper end of arm 12 is bent at substantially right angles into a leg 14, which is imbedded in the base 10. At 13' arm 12' is similarly bent into a leg 14'. The arms 12—12' are inclined inwardly from their outermost points adjacent their upper ends to a point 15, immediately above 80

their lower extremity. At 15 they are closest to the base 10. The arms describe a curve which, when viewed from a point adjacent the base, is convex. The holder is not positioned at a sharp angle with respect to the base 12, so that room is provided for the insertion of an article 16. The base is scooped marginally at 17 and this promotes also the facility of insertion of the towel or other article that is to be suspended by 85 the hanger. When the article is moved upwardly between the ball 18 and the base 10, the ball is moved upward readily as the arms 12—12' of the holder diverge from the base and there is no frictional or other influence tending to prevent upward movement of the ball. The fact that the arms 12—12' diverge upwardly, provides more room for the ball. The divergence of the arms 12—12' provides room, also, for the 90

insertion of a screw not shown in the countersunk hole 19 between the upper ends of the arms. After the article has been inserted 95

2

ed into position, the ball 18 drops downwardly and frictionally grips the article. The inward inclination of the hole towards the base 10 causes the ball to fit more tightly 5 against the base as the ball is urged downwardly. Consequently the weight of the article 16 does not tend to release the grip of the ball, but rather increases its firmness. The divergence upwardly of the arms 10 12-12' operates to accentuate this effect, since, as the ball moves downwardly, the arms 12-12' are closer together at lower levels and consequently tend to force the ball against the base 10. Each of the arms 15 12-12' is substantially L-shaped in side view, and the wire forming the holder is of the shortest length possible for the accomplishing of the functions intended; as the wire is short, less leverage can be exerted 20 thereon than if it were long. The shape of the wire, including the holder and the legs 14-14', results in a structure of the greatest strength and durability. The legs 14-14' are positioned by being inserted in base 10 until their ends are flush with the rear surface thereof. This may be done by 25 resting the base on a flat member and driving the legs in until they contact with the member. When this position is reached, the arms 12-12' are spaced properly from the base so as to cooperate with the ball 18. An accurate adjustment of the holder with 30 respect to the ball may, therefore, be effected in a very convenient manner.

35 The base 10 may be made of yielding material, such as soft wood, though obviously other materials may be used. Where the base is soft and yielding, an especial frictional or gripping action of the ball results 40 by reason of the tendency of the base to conform to the curvature of the ball; whereby the release of the ball is impeded and an effective grip on the article suspended re-

sults. In its lower or gripping position, the ball has a three-point contact. It abuts 45 against arm 12' and base 10. The three-point contact operates to promote the relative action of the ball. The arms 12-12' prevent lateral movement of the ball, so that there is less danger of disengagement thereof. With the arms 12-12' contacting directly with the ball, all possibility of lateral movement thereof in its lower position is prevented. The contact of the ball with the article 16 is such as not to tear the article, as might be the case if two similar arms, such as 12-12', were provided for contact with the ball instead of base 10. The suspension of an article between the ball and strands of wire tends to cut the 50 fabric.

I claim:

The combination of a flat base of material thickness, a gripping ball associated therewith, a wire U-shaped holder therefor, the arms of the U being slightly divergent upwardly, a leg continuous with one of the arms of the holder and bent away therefrom at substantially a right angle, a second leg continuous with the other of said arms 65 and bent away therefrom at substantially a right angle, said legs being imbedded in said base, and a ball retained by said holder and said base, said holder extending inwardly from the top thereof to a point 70 slightly above the lower end thereof, the lower end being spaced from the base to facilitate the insertion of an article to be suspended, whereby an article may be detachably held between said base and ball 75 and wedged directly against said base.

In testimony that I claim the foregoing I have hereunto set my hand at Milwaukee, in the county of Milwaukee, and State of Wisconsin.

EMIL L. KAMRATH.
